UNITED STATES PATENT OFFICE.

WARD EVANS, OF WASHINGTON, DISTRICT OF COLUMBIA.

DESIGN FOR A TROUSERS-HANGER.

SPECIFICATION forming part of Design No. 26,975, dated April 27, 1897.

Application filed March 19, 1897. Serial No. 628,353. Term of patent 7 years.

To all whom it may concern:

Be it known that I, WARD EVANS, a citizen of the United States, residing in the city of Washington, District of Columbia, have invented and produced a new and original Design for a Trousers-Hanger, of which the following is a specification.

In the accompanying drawings, Figure 1 is a perspective view of the hanger. Fig. 2 is an end view of the same. Fig. 3 is a horizontal section on line 3 3 of Fig. 1.

The leading feature of the design consists in the hook-like or loop portions *a* of the device, which are arranged parallel to each other

and extend laterally from the respective parallel shanks or arms *b* and at right angles thereto. The said shanks or arms *b* are crossed at about the middle of their length, their upper portions being separated more widely than their lower ones and terminating in a coil *c*.

What I claim is—

The design for a trousers-hanger, as shown and described.

WARD EVANS.
